CLAIM

The ornamental design for a display screen portion with icon for sphygmomanometer, as shown and described.

DESCRIPTION

FIG. 1 is a front view of a first embodiment of a display screen portion with icon for sphygmomanometer showing my new design.

FIG. 2 is a front view of a second embodiment of a display screen portion with icon for sphygmomanometer showing my new design; and,

FIG. 3 is a front view of a third embodiment of a display screen portion with icon for sphygmomanometer showing my new design.

(Continued)

The broken lines illustrate a portion of the display screen and form no part of the claimed design. The solid black shading depicts a color contrast.

1 Claim, 3 Drawing Sheets
